(57) **CLAIM**

The ornamental design for a video camera cable, as shown and described.

DESCRIPTION

FIG. 1 is a top, front and left side isometric view of a video camera cable in accordance with the new design;

FIG. 2 is a top, front and left isometric view thereof;

FIG. 3 is a top, front and right side isometric view;

FIG. 4 is an alternative top and front isometric view thereof;

FIG. 5 is an enlarged top and right side isometric view of a cable connector portion, the cable shown in FIGS. 1-4 is omitted for ease of illustration; and,

FIG. 6 is an enlarged bottom plan view of a cable connector portion, the cable shown in FIGS. 1-4 omitted for ease of illustration.

The broken lines shown in FIGS. 5 and 6 represent the bounds of the claimed design and form no part of the claimed design.

1 Claim, 6 Drawing Sheets

FIG. 2

FIG. 3

FIG. 4
